US0D1103928S

(12) **United States Design Patent** (10) Patent No.: **US D1,103,928 S**
(45) Date of Patent: ** Dec. 2, 2025

(54) **CONNECTOR PORTION**

(71) Applicant: **RELIANCE WORLDWIDE CORPORATION**, Atlanta, GA (US)

(72) Inventors: **Joseph Derres Catalano**, Roswell, GA (US); **Sai Kishore Ravisankar**, Alpharetta, GA (US)

(73) Assignee: **Reliance Worldwide Corporation**, Atlanta, GA (US)

(**) Term: **15 Years**

(21) Appl. No.: **29/913,674**

(22) Filed: **Oct. 6, 2023**

(51) LOC (15) Cl. **23-01**

(52) U.S. Cl.

USPC **D23/262**

(58) **Field of Classification Search**

USPC ... D13/133, 101, 123, 146, 147, 153, 137.1, D13/149, 139.8, 182; D14/435.1, 433; D23/259, 262

(57) **CLAIM**

The ornamental design for a connector portion as shown and described.

DESCRIPTION

FIG. 1 is a perspective view of the connector portion according to the new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines in the drawings are for the purpose of illustrating portions of the article that form no part of the claimed design.

1 Claim, 4 Drawing Sheets
